LOCOMOTIVE STOKER

Charles J. Surdy, Tuckahoe, N. Y., assignor to
 The Standard Stoker Company, Incorporated,
 a corporation of Delaware

Application June 23, 1938, Serial No. 215,323

3 Claims. (CL 110—105.5)

This invention relates to stokers adapted to feed through an opening in a furnace wall, and more particularly, to an improved stoker for firing a locomotive boiler firebox through the usual hand firing opening in the firebox back-wall.

An object of the invention is to provide a stoker of the type described that obstructs a minimum of space at the firing opening leaving the greater portion of the opening unobstructed permitting convenient access to the firebox for manual delivery of fuel or for the purpose of entry into the firebox.

More specifically, an object of the invention is to provide a stoker of the type described applicable to a locomotive firebox without enlarging the conventional hand firing opening and providing an unobstructed space in the firing opening permitting convenient access to the firebox for manual delivery of fuel or for the purpose of entry into the firebox.

Further objects and advantages of the invention reside in the novel construction of parts and the novel combination and relation of elements, all as brought out in the following description and the appended claims.

Fig. 1 is a view in longitudinal central vertical section of the locomotive boiler backhead through the firing opening therein with the novel stoker shown applied thereto in similar section and partly in elevation;

Fig. 2 is a view in plan section taken on the line 2—2 of Fig. 1;

Fig. 3 is a view in section on the line 3—3 of Fig. 1;

Fig. 4 is a view in end elevation of the fire-door flange and firedoor with the stoker conduit applied thereto;

Fig. 5 is a view in elevation from within the firebox showing the firing opening and the distributing mechanism of the stoker applied thereto;

Fig. 6 is a sectional view taken on the line 6—6 of Fig. 2; and

Fig. 7 is a view similar to the view of the construction shown in Fig. 3, showing a modified form of the stoker.

The invention is shown for purpose of illustration as applied to a locomotive firebox, though it will be apparent from the following description that it is applicable as well to other types of fireboxes.

In the drawings, a locomotive, indicated generally by the numeral 10, is provided with a firebox 11 having a boiler backhead 12 provided with

5 a conventional firing opening 13 therein. A cab deck 14 extends rearwardly from the backhead 12 below the level of the firing opening 13. The conventional firing opening is of general elliptical shape, measuring 20 inches along its major diameter and 16 inches along its minor diameter.

The stoker is indicated generally by the numeral 15, only so much thereof being shown as is essential to a complete understanding of 10 the invention. The portion of the stoker conveying fuel forwardly from the tender to the locomotive may be of any suitable construction well known in the art. The stoker includes a discharge conduit 16 extending upwardly and forwardly from a position beneath the cab deck 14, the delivery opening thereof being adjacent 15 one side of the lower portion of the firing opening. The discharge conduit 16 includes a tubular conduit 17 offset at one side of the vertical longitudinal central plane of the firing opening and an elbow shaped conduit 18 secured to the upper end of the tubular conduit 17 by suitable 20 means, such as the bolts 19, passing through the circumferentially extending flanges 20 and 21 of the conduit 17 and elbow 18, respectively.

A frame 22, preferably, though not necessarily, formed as an integral part of the elbow 18, embraces the firing opening 13 and is secured to the backhead 12 by suitable means, as by the bolts 23 passing through the flange 22a of the frame. The elbow 18 communicates with the frame 22 through an opening 24 in the lower portion of the side wall 25 of the frame 22 and fuel is urged upwardly through the tubular conduit 17 25 and elbow 18 and into the frame 22 by a screw conveyor 26. The frame 22 is open at its rearward end, the opening being substantially the same size as the firing opening. A pair of door members 27 and 28 are mounted at the upper 30 rearward end of the frame 22 which, during normal operation of the stoker, form a closure for the firing opening 13. The door members 27 and 28 are preferably arranged to swing laterally in opposite directions and upwardly, and when open permit manual introduction of fuel 35 through the tunnel formed by the frame 22 and into the firebox and also permit entry into the firebox.

The frame 22 carries a fuel distributing means 40 including a chambered pressure fluid distributor head 29 and a distributing table 30, the distributor head 29 being seated on the bottom wall 31 of the frame 22 adjacent the opening 24 in the sidewall 25 of the frame, and the distributing table 30 is secured to the frame by bolts 32 passing

ing through a flange 33 depending from the bottom wall 31 of the frame. A reduced portion 35 of the distributor head 29 extends through an opening 36 in the bottom wall 31 of the frame and a pipe 37 leading from a suitable source of fluid under pressure is threaded in the lower end thereof for supplying pressure fluid to chamber 38. A bolt 39 extending through a flange 40 formed with the elbow 18 and through the bottom wall of the frame, is threaded into the distributor head securing it in place.

The distributing table 30 is preferably of the type having a removable forward portion, so that the forward portion which is most exposed to the heat of the firebox, can be replaced without requiring replacement of the entire distributing table. The table 30 is disposed closely adjacent the lower margin of the firing opening and the distributor head 29 is at the rear of and at one side of the table so that when the door members 27 and 28 are opened, practically the entire firing opening is available for hand firing or for gaining access to the firebox.

The front face 41 of the distributor head 29 is provided with a plurality of jet openings 42 communicating with the chamber 38. The plane of the front face 41 is angularly disposed with respect to the central vertical longitudinal plane of the firing opening and the jet openings are directed across all parts of the distributing table 30 so that the pressure fluid blast issuing from the jet openings 42 projects fuel from the table 30 into the firebox. Ribs 43 and 44, one on each side of the upper surface of the table 30 curve forwardly and laterally toward a respective rear corner of the firebox for deflecting a portion of the fuel to the rear corners.

With the jet head 29 at one side of the table 30, with its front face angularly disposed and the jet openings 42 directed across all parts of the table, most of the fuel would normally be projected to that side of the firebox toward which the jet head 29 faces. To provide for even distribution of fuel over all parts of the firebed in the firebox, a plurality of ribs 45 are provided on the top surface of the table 30 between the ribs 43 and 44, curving forwardly and laterally toward that side of the firebox that would normally receive less fuel.

In Fig. 7 is shown a modified form of the invention in which the screw conveyor 26a, instead of extending into the elbow 18, as in the preferred form of the invention, is terminated within the straight tubular conduit portion 17. In this construction, the fuel is forced through the elbow 18 by the pressure exerted against the fuel by the screw conveyor 26a, while in the preferred form of the invention, the screw conveyor 26 conveys the fuel directly to the distributor head 29.

I claim:

1. In combination with a furnace having an upright wall provided with a firing opening, a stoker including a fuel elevator having a delivery opening adjacent said upright wall and at one

side of the central longitudinal vertical plane of the firing opening, a plate centrally disposed in said firing opening adjacent the lower margin thereof, said plate arranged to receive fuel from said fuel elevator on a rear corner portion of its upper surface, and a pressure fluid distributor adjacent the delivery end of said fuel elevator and adjacent the lower lateral extremity of said firing opening and wholly at one side of said plane, said distributor being adapted for the emission of fluid under pressure across the full width of the upper surface said plate for protecting the fuel from the rear corner portion of said plate into the firebox.

2. In combination with a furnace having an upright wall provided with a firing opening, a stoker including a substantially straight riser conduit having its upper end disposed at one side of the central longitudinal vertical plane of the firing opening and an elbow-shaped conduit at the upper end of said straight riser conduit, said straight riser conduit being so disposed that the extension of a vertical plane passing longitudinally through the riser conduit intersects the backhead at one side of the firing opening therein, said elbow-shaped conduit having its delivery end adjacent said upright wall at one side of the central longitudinal vertical plane of the firing opening and opening laterally with respect to said riser conduit toward said last-named plane, means for urging fuel through said riser conduit and said elbow-shaped conduit, a plate centrally disposed in said firing opening adjacent the lower margin thereof, said plate arranged to receive fuel from said elbow-shaped conduit on a rear corner portion of its upper surface, and a pressure fluid distributor adjacent the delivery end of said elbow-shaped conduit wholly at one side of said last-named plane and adjacent the lower lateral extremity of said firing opening arranged for emission of fluid under pressure across said plate for projecting the fuel from the rear corner portion of said plate into the firebox.

3. In combination with a furnace having a grate and an upright wall provided with a firing opening, a stoker including a fuel feed conduit having a delivery opening adjacent said upright wall and at one side of the central longitudinal vertical plane of the firing opening, a pressure fluid distributor head adjacent the delivery end of said fuel feed conduit wholly at one side of said plane and adjacent a lateral extremity of said firing opening, said distributor head being arranged to issue blasts of pressure fluid from the said lateral extremity of the firing opening obliquely thereinto, means for urging fuel into the zone of action of the pressure fluid distributor head and means spaced forward and at one side of said distributor head constructed and arranged to divert a portion of the obliquely projected fuel forwardly and laterally in the opposite direction.

CHARLES J. SURDY.
